UNITED STATES PATENT OFFICE.

FRED ASHWORTH, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

THREAD-WAXING DEVICE.

Application filed June 15, 1920. Serial No. 389,142.

To all whom it may concern:

Be it known that I, FRED ASHWORTH, a citizen of the United States, residing at Beverly, in the county of Essex and State 5 of Massachusetts, have invented certain new and useful Improvements in Thread-Waxing Devices; and I do hereby declare the following to be a full, clear, and exact description of the invention, such as will enable others skilled in the art to which it appertains to make and use the same.

The present invention relates to thread waxing devices for applying melted wax to sewing thread.

15 An object of the present invention is to provide novel and improved means in a thread waxing device for guiding the thread through the wax in the wax receptacle and for stripping the superfluous wax from the 20 thread as it leaves the receptacle.

Another object of the present invention is to provide novel and improved means in a thread waxing device for heating the wax receptacle.

25 With these and other objects in view, the features of the present invention consist in certain constructions, arrangements, and combinations of parts hereinafter described and claimed, the advantages of which will 30 be obvious to those skilled in the art.

The several features of the present invention will be clearly understood from the following description and accompanying drawings, in which:

35 Figure 1 is a vertical sectional view of a thread waxing device embodying the features in their preferred form, which is shown mounted on the frame of a sewing or other machine; Fig. 2 is a plan view of 40 the device; Fig. 3 is a front elevation of the lower portion of the device; Fig. 4 is a sectional view, partly in elevation, taken on the line 4-4 of Fig. 1; and Fig. 5 is an enlarged detailed sectional view, partly in 45 elevation, of the thread guiding and wax stripping means.

The embodiment of the invention illustrated in the drawings is provided with a wax receptacle 2 and a heating device 4 mounted upon a bracket 6 which is illustrated as being secured to a portion of the frame 8 of the machine. The wax receptacle is provided with a substantially cylindrical wall 9 having a rearwardly projecting lug 10 which is in sliding engagement with

a supporting pin 12 having its lower end secured in an aperture in the bracket 6, the supporting pin extending through an aperture in the lug. The bottom of the wax receptacle rests upon a collar or nut 14 screw-threaded on a stud 16 having its lower end reduced in diameter and removably clamped in a split collar 18 formed on the forward end of the bracket 6. The bottom wall of the wax receptacle is shaped to 60 form a downwardly opening channel or pocket 20 which is U-shaped in cross-section and extends diametrically across the bottom of the wax receptacle. The heating device comprises a steam chamber 22 which is 65 shaped to fit the pocket 20 and is provided with an inlet 24 in its rear end and an outlet 26 in its forward end. The steam chamber 22 is secured to the bracket 6 by means of the stud 16, the stud and chamber being 70 made integral. With this construction it will be apparent that by turning the nut 14 the wax receptacle may be moved longitudinally on the supporting pin 12 to adjust the inner portion of the pocket 20 toward 75 and from the top portion of the steam chamber 22, the sides of the pocket and steam chamber remaining in contact. Such adjustment of the wax receptacle may be conveniently utilized to regulate the degree of 80 heat radiated from the steam chamber to the wax in the wax receptacle. By adjusting the wax receptacle upwardly the air space thereby provided between the upper portion 85 of the steam chamber and the inner portion of the socket 20 results in a decrease in the degree of heat radiated to the wax in the wax receptacle, the adjustment of the wax receptacle downwardly results in an increase 90 in the degree of heat radiated to the wax, and when the wax receptacle has been adjusted to bring the inner portion of the pocket 20 into contact with the upper portion 95 of the steam chamber, the maximum degree of heat is radiated to the wax. 100

The top of the wax receptacle is closed by a cover 28 secured by screws 30 thereto. The cover 28 is provided with the usual opening 34 through which wax may be supplied to the wax receptacle. The thread 105 waxing device is preferably positioned when mounted on the frame of a sewing machine to bring the opening 34 directly beneath a removable cover 36 which may constitute a 110 table on the front of the machine, the cover

preventing foreign substances from entering the receptacle.

The illustrated thread waxing device is designed for use on outsole lockstitch shoe sewing machines and accordingly the device is provided with two sets of thread guiding and stripping devices, one for the bobbin thread and the other for the needle thread. These devices comprise collars 38, the lower portions of which are reduced and extend into apertures 40 in the cover 28 and are adapted to turn therein. In the collars 38 are mounted thread guides 42 having projecting flanges which engage the top surfaces of the collars 38. The thread guides 42 are formed on the outer ends of bars 44, the inner ends of which bars are supported by a boss 46 centrally formed on the top surface of the cover 28. The thread guides 42 and the collars 38 are clamped to the cover 28 by means of screws 48 which extend through apertures in the bars 44 and are threaded into the cover. The collars 38 are provided with depending lugs 50 to which are secured rods 52, the upper ends of the rods being secured in sockets in the lugs 50. The rods 52 are bent at right angles to provide transverse portions 54 and the lower ends of the rods are bent to embrace the usual thread eyes 56 which are arranged at opposite sides of the wall of the pocket 20.

The threads enter the wax receptacle through apertures or thread eyes 58 in the thread guides 42 and after passing through the thread eyes 56 which are immersed in the wax, pass through thread eyes 60 in the thread guides 42. The stretches of each thread extending between the thread guide 42 and the thread eye 56 of each thread guiding and stripping device, pass across opposite sides of the transverse portion 54 of the rod 52 and are entwined or twisted about each other between the transverse portion of the rod 52 and the thread guide 42. To enable the thread guiding and stripping devices to be easily threaded, as above described, each device may be removed and replaced upon unscrewing the screw 48 from the cover of the receptacle.

The stripping action of the devices is accomplished by the twist placed in the stretches of the threads between the thread guides 42 and the transverse portions of the rods 52, the stretches of thread entering the receptacle acting to wipe or strip the superfluous wax from the stretches of thread leaving the receptacle. It will be apparent that by varying the amount that the stretches of each thread are thus twisted that the stripping action may be varied as desired and this may be readily accomplished by loosening the clamping screw 48 and turning the collar 38 the required amount.

While it is preferred to employ the specific construction and arrangement of parts illustrated and described, it is to be understood that this construction and arrangement is not essential except so far as specified in the claims and may be changed or modified without departing from the broader features of the invention.

The nature and scope of the present invention having been indicated and a device embodying the several features of the invention in their preferred form having been specifically described, what is claimed is:

1. A thread waxing device having, in combination, a wax receptacle, and means to guide the thread through the wax in the receptacle and to cause the stretches of the thread leading to and from the wax to be twisted about each other, said means having provision for adjustment to vary the amount that the stretches of thread are thus twisted.

2. A thread waxing device having, in combination, a wax receptacle, and means to guide the thread through the wax in the receptacle and to cause the stretches of the thread leading to and from the wax to be twisted about each other comprising a rod having a portion extending transversely between the stretches of the thread, and means for turning the rod to vary the amount that the thread is thus twisted.

3. A thread waxing device having, in combination, a wax receptacle, means to guide the thread through the wax in the receptacle and to cause the stretches of the thread leading to and from the wax to be twisted about each other comprising a rod extending into the receptacle having a transverse portion extending between the stretches of the thread, a thread guide mounted on the inner end of the rod, and means for turning the rod to vary the amount that the stretches of thread are thus twisted.

4. A thread waxing device having, in combination, a wax receptacle, means to guide the thread through the wax in the receptacle and to cause the stretches of the thread leading to and from the wax to be twisted about each other comprising a thread guide for separately guiding the stretches of the thread leading to the wax, a member extending transversely between the stretches of the thread and interposed between the thread guide and the wax, and means for relatively turning the thread guide and said member to vary the amount of twist in the stretches of the thread.

5. A thread waxing device having, in combination, a wax receptacle, a cover therefor, a block secured to the cover having a pair of apertures for guiding the thread into and out of the receptacle, a supporting member mounted in the cover for rotation about said block, a rod carried by the supporting member extending into the recep-

- tacle having a transverse portion extending between the stretches of the thread leading into and out of the receptacle, and a thread guide mounted on the inner end of the rod.
5. 6. A thread waxing device having, in combination, a wax receptacle having the outside of one wall shaped to form a pocket, a heating element shaped to fit the pocket, and means for relatively adjusting the receptacle and heating element toward and from each other.
7. A thread waxing device having, in combination, a wax receptacle having its bottom wall shaped to form a pocket opening downwardly having its upper portion substantially semi-cylindrical, a heating element shaped to fit the pocket, and means for relatively adjusting the receptacle and heating element toward and from each other to vary the relative position of the heating element and the inner wall portion of the pocket.
8. A thread waxing device having, in combination, a wax receptacle having its bottom wall shaped to form a pocket opening downwardly, a heating element shaped to fit the pocket, a shank projecting downwardly from the heating element, and a nut threaded on the shank and supporting the receptacle capable of being adjusted on the shank to vary the relative position of the top of the heating element and the inner portion of the pocket.
9. A thread waxing device having, in combination, a wax receptacle having its bottom wall shaped to form a pocket U-shaped in cross-section and opening down-
wardly, a heating element shaped to fit the pocket, and means for relatively adjusting the receptacle and heating element to provide a space between the top portion of the heating element and the inner portion of the pocket while the side walls of the heating element and pocket remain in contact.
10. A thread waxing device having, in combination, a wax receptacle, means for supporting the wax receptacle comprising a lug projecting from the longitudinal wall of the receptacle provided with an aperture extending longitudinally of the receptacle, and a supporting pin extending into the aperture, a heating element located beneath the receptacle, and means for moving the receptacle on the supporting pin in a direction toward and from the heating element to vary the amount of heat supplied to the wax in the receptacle.
11. A thread waxing device having, in combination, a wax receptacle, and means to guide the thread through the wax in the receptacle and to cause stretches of the thread to be twisted about each other, said means having provision for adjustment to vary the amount that the stretches of thread are thus twisted.
12. A thread waxing device having, in combination, a wax receptacle, and thread guiding and stripping devices arranged to guide the thread through the wax in the receptacle and having provision for adjustment to vary the stripping action on the thread.

FRED ASHWORTH.
